UNITED STATES PATENT OFFICE.

MARIA CODY, OF ST. LOUIS, MISSOURI.

DESIGN FOR A BREAD-BOX.

SPECIFICATION forming part of Design No. 29,758, dated December 6, 1898.

Application filed October 17, 1898. Serial No. 693,830. Term of patent 7 years.

To all whom it may concern:

Be it known that I, MARIA CODY, a citizen of the United States, residing in St. Louis, Missouri, have invented and produced a new and original Design for Bread-Boxes, of which the following is a specification.

The figure is a perspective view of a bread-box embodying my design.

As shown in the drawing, the leading or essential feature of my new design for a bread-box consists of a rectangular body having perforations and having the rounded or arched top reaching from the ends.

Referring by numerals to the drawing, 1 is the rectangular body. 2 are the perforations, 15 and 3 is the rounded or arched top reaching from one end to the other of the rectangular body.

I claim—

The design for a bread-box substantially as 20 herein shown and described.

MARIA CODY.
